ROCKET-LAUNCHING TOY

John W. Ryan, Los Angeles, and John H. Northrop, La Canada, Calif., assignors to Mattel, Inc., a corporation of California

Filed Feb. 1, 1967, Ser. No. 5,659

Term of patent 14 years

(Cl. D34—15)

FIG. 4

FIG. 5

FIG. 6

FIGURE 1 is a side elevational view of a rocket-launching toy showing our new design;

FIGURE 2 is a top plan view thereof;

FIGURE 3 is an end elevational view taken from the left of FIGURE 1;

FIGURE 4 is a side elevational view of the side opposite FIGURE 1;

FIGURE 5 is a bottom, plan view looking up at FIGURE 4; and

FIGURE 6 is an end elevational view taken from the right of FIGURE 1.

The dotted line portions shown are typical rockets and are for purposes of its illustration only.

We claim:

The ornamental design for a rocket-launching toy, as shown and described.
